CUTTER

Erwin W. Gohr, Milwaukee, Wis.

Application November 18, 1940, Serial No. 366,131

3 Claims. (Cl. 164—73)

My invention relates to improvements in cutters.

The object of my invention is to provide a cutter principally used for cutting sheet material and which will not only cut such material continuously throughout considerable length thereof, but may also be used to cut material surfaced with substances which would be classed as abrasives.

Other objects of my invention include the provision of means for advancing and retracting material alternatively through the throat of my cutter and means for mounting my material cutter on a staging or other support where workmen must be accommodated while working on vertical surfaces.

In the drawings:

Figure 1 is a side elevation of my cutter.

Figure 2 is a plan view of my cutter.

Figure 3 is a side elevation showing portions 20 of the mechanism broken away to exhibit interior construction.

Figure 4 is a section on line 4—4 of Fig. 1.

Figure 5 is a section on line 5—5 of Fig. 3.

Figure 6 is a side elevation of my cutter 25 mounted upon a staging and staging clamp.

Like parts are identified by the same reference characters throughout the several views.

My cutter is especially suited to the cutting of sheet material such as the imitation brick popularly used to cover the exterior surfaces of buildings. This sheet material is usually composed of bagasse or other waste cellulose material with a surfacing of asphalt and gravel. Such material has been found very difficult to trim or cut, since any slicing or sawing action necessarily brings cutting edges against the abrasive material and against the sticky asphalt which soon spoils the edge of the cutting instrument. Furthermore, sheet material of this type is usually made up in broad sheets, the cutting of which would be most economically and efficiently handled in a continuous cutting operation, but because of the high resistance to the cutting instrument through the material it has generally been considered necessary to place the sheet against a stop while the cutting progresses. This has, of necessity, forced the cutting to be done in successive stages, requiring laborious resetting of the work against the stop.

Another problem in the cutting of sheet material is that when notches are to be cut it is often extremely difficult to cause the knife or other cutting instrument to retreat from a kerf so that the material may be repositioned in the cutting 55

instrument to make a new kerf in a different direction.

My new cutter meets the various problems referred to above as will be seen from the following descriptions of the parts thereof and the manner in which my cutter is used.

Structurally, my cutter, as shown in Figs. 1 to 5 inclusive, includes a main frame 10 shaped as a C jaw unit, an adjustable bed 11 for the lower jaw 12, a quick acting clamp 13 for the upper jaw 14, a knife guide 15 for the knife 16 incorporated in the upper jaw 14 and a handle 17 for simultaneously operating the quick acting clamp 13 and the knife 16.

Sheet material 18 of the type above described and including bagasse 19 and asphalt and gravel 20 for the surface thereof may be received by the bed 11 and the quick acting clamp 13 to be cut and to be passed to the right as shown in Figs. 1 to 3 of the drawings, and the material at either side of the kerf formed by the knife 16 will pass at either side of the frame 10, at the innermost portion of the C shape thereof as shown in Fig. 5 where it will be seen that the web 21 is offset laterally at 22 with a shelf 23 therebetween so that the material may be elevated on one side of the kerf and depressed on the other side of the kerf and thus enable the material to be passed in one continuous operation 30 through my cutter.

The bed 11 is slotted at 25 and 26 to receive bolts 27 and permit of adjustment whereby to accommodate various thicknesses of material 18 and to place the knurled surface 28 of the bed 35 in parallelism with a friction surface 29 which forms the operating face of the quick acting clamp 13. Quick acting clamp 13 includes a bifurcated arm 30 pivotally mounted at 31 and horn shaped portion 32 of the upper jaw 14 of 40 the frame extends through the opening 33 in the bifurcated arm.

Double linkage comprising a toggle with U shaped strap 35 and duplicate links 36 at either side of the horn 32 carries the quick acting clamp 45 13, since the duplicate links 36 are pinned to the arm 30 at 37 and pinned to the U shaped strap 35 at 38 and the U shaped strap is mounted on oscillatable pin 39 which is carried in the horn 32 which is arcuately slotted at 40. The pin 39 50 is provided with a spring 41 and is shaped to be slightly withdrawn and snapped from one end of the slot to the other for reasons about to be described.

Handle 11 has a floating fulcrum 45 on the end of a link 46 which is pivotally mounted on

pin 38 forming part of the toggle mechanism above described. The load end of the handle 17 is pivoted at 47 to the end of knife slide 48 and since the knife slide 48 is mounted in guide 15 the knife 16 carried by the knife slide 48 can only reciprocate along straight lines in the center of a slot 49 formed in the quick acting clamp 13.

As shown in Fig. 4 the bed is slotted at 34 and the margins of the slotted bed are ribbed at 340. When the quick acting clamp is brought down upon the material and presses it against the bed 11, the material to be cut is most heavily compressed along the margins of the slot and, therefore, most heavily compressed at either side of the line to be followed by the knife in cutting the material.

The operation of the handle and its associated parts is, therefore, as follows: Commencing in a cycle with the parts in the position shown in Fig. 1 the free end 50 of the handle is raised and since the shape of the handle and the relation of the pivot pins 38, 45 and 47 is as indicated in Fig. 1 the first movement tends to raise the pin 45 and to pull forwardly upon pin 38, thus lifting the quick acting clamp 13. Assuming that the knife is embedded in the sticky asphalt 20 there is considerable resistance to the movement of the knife through the material 18 and when the clamp has been elevated sufficiently to release the material 18 the further movement of the end 50 of the handle and the limitation upon the upward movement of the clamp 13 by a stop 130 will then cause the pin 45 to be the fulcrum of further movement of the handle, and the knife, together with the material 18 will be moved into the jaws of the frame 10. When the handle has been sufficiently swung so that the knife slide 48 has reached the end of the guide 15 as shown in Fig. 3, the handle will stop and may then be swung in the opposite direction. The first movement in the downward direction of the handle will thrust the pin 45 toward the right, and the toggle linkage 35-36 will press the quick acting clamp downwardly upon the material 18 until the material has been firmly clamped. Then further movement of the handle will cause the knife 16 to be advanced in a cutting operation, since the slide 48 will be withdrawn from the guide 15 and will carry the knife forwardly in a slicing operation which will continue until the handle has reached the position shown in Fig. 1, thus completing the cycle which may be repeated as often as is necessary to complete the length of cutting desired in the material 18.

If the cut is only to progress part way through a sheet 18 and the knife has reached the end of such a cut the knife may be withdrawn from the kerf by "reversing" the mechanism. This is accomplished by pulling the pin 39 to unlock the U shaped member 35 and swing it to the position shown in dotted lines in Fig. 1, thus reversing the toggle and reversing the effect of the movement of the handle 17 so far as clamping action is concerned, since the raising of the handle will thereafter cause the material to be clamped while the knife retreats in the kerf and causes the material to be released from the clamping operation while the knife and the sticky material are moved out of my cutter as the handle descends.

At one side of the frame 10 I provide a dove-tail boss 60 receivable in a dove-tail slide complementary thereto formed as part of a standard 61. Standard 61 in turn is receivable in a staging clamp 62, the upper member 63 of which and the lower member 64 are shown clearly in Fig. 6. The lower member 64 has a threaded guide 65 receivable in a tubular boss 66 on the clamp 62. A clamp bolt 67 threaded into the boss 66 pulls the clamping surfaces 63 and 64 together upon a staging board 68 or other staging member upon the usual staging board receiver 69 on ladder 70. When in position upon the standard 61 my cutter is in position to receive large sheets of material in handy working relationship to any workman standing on the staging board 68.

From the above description it will be seen that the knife 16 as it is reciprocated upon slide 48 in guide 15 has portions of its blade constantly presented to the relatively easily severable substances 19 of which the material is made, whereas another portion of the knife blade is constantly presented to separate the asphalt and abrasive material which does not require special keenness of blade edge. I have found that after hours of constant use, the portion of the blade presented to the cellulose material has retained its keenness and that the other portion presented to the abrasive has assumed a degree of bluntness not at all detrimental to its portion of the work. I have also found that sheets of material eight feet long or longer may be passed with a considerable degree of accuracy of alignment through my cutter without serious distortion of the material at 21-22 at the base of the C frame as shown in Fig. 5.

I claim:

1. A cutter including a C frame with one jaw having a work clamping bed, a pivotally mounted work clamping member on said frame, and a toggle link to support the clamping member adjustably with reference to the clamping bed, and a knife blade and knife blade operating arm connected to the center member of said toggle link whereby the operation of the handle will alter the adjustment of said clamp member.

2. A cutter including a C frame with one jaw having a work clamping bed, a pivotally mounted work clamping member on said frame, and a toggle link to support the clamping member adjustably with reference to the clamping bed, and a knife blade and knife blade operating arm connected to the center member of said toggle link whereby the operation of the handle will alter the adjustment of said clamp member, one end of the toggle being provided with an adjustable connection to the frame whereby to reverse the reaction of the clamp member.

3. In a device of the character described, a C frame, one jaw of which includes a knife guide and a knife therefor, a handle provided with a fulcrum connection and a connection to the knife guide, said fulcrum connection extending to the intermediate articulation of a toggle, a clamp arm, and a toggle provided with an intermediate articulation and extending between the frame and said clamp arm whereby the movement of the handle will clamp or release the clamp arm.
